UNITED STATES PATENT OFFICE.

CHARLES CUNO, OF MERIDEN, CONNECTICUT, ASSIGNOR TO THE CONNECTICUT TELEPHONE & ELECTRIC COMPANY, INCORPORATED, OF MERIDEN, CONNECTICUT, A CORPORATION OF CONNECTICUT.

MAGNETO INTERRUPTER AND TIMER.

1,029,914.

Specification of Letters Patent. Patented June 18, 1912.

Application filed January 11, 1910. Serial No. 537,412.

To all whom it may concern:

Be it known that I, CHARLES CUNO, a citizen of the United States, residing at Meriden, county of New Haven, State of Connecticut, have invented certain new and useful Improvements in Magneto Interrupters and Timers, of which the following is a full, clear, and exact description.

My invention relates to electrical apparatus, and is particularly concerned with improvements in the construction and arrangement of the interrupter or circuit breaker and of the distributor of magneto electric machines, which are especially, though not exclusively, adapted for use in ignition systems for internal combustion engines.

The object of my invention is to provide a construction of interrupter which may be easily inspected while in operative position, and at the same time may be completely and bodily removed from the magneto for adjustment and repair.

A further object is to provide an adjustment of the contact members of the interrupter and of the distributor with respect to the operating lever of the interrupter to readily adapt the magneto for both right and left drive, whereby the magneto as a whole may be mounted upon either side or at either the front or rear of the driving mechanism.

A further object is to provide for easy relative adjustment of the contact points of the interrupter without disturbing the mounting of the contact arms.

The invention further contemplates means for readily shifting the distributor arm of the distributor to correspond with the adjustment of the interrupter for right and left drive.

With these and other objects in view as will appear from the following detailed description the invention consists in the construction and relative arrangement of parts, a preferred embodiment of which is illustrated in the accompanying drawings, in which,

Figure 1 is an end elevation of a magneto showing the interrupter end. Fig. 2 is a side elevation of the parts shown in Fig. 1. Fig. 3 is a view corresponding to Fig. 1 with the caps covering the interrupter mechanism and the distributor mechanism respectively, removed. Fig. 4 is a partial,

vertical sectional view on the line $x-x$, 55 Fig. 1, showing the interrupter and distributor and adjacent co-operating parts of the magneto. Fig. 5 is an enlarged view of the interrupter support with the interrupter removed therefrom. Fig. 6 is a rear view of the interrupter carrier showing the adjusting lever. Fig. 7 is a side view of said carrier. Fig. 8 is a detailed view of the fixed contact member of the interrupter and the base plate therefor, shown in edge and 65 face view respectively. Fig. 9 is a view similar to Fig. 7 of the movable contact member of the interrupter. Fig. 10 is a sectional view of a detachable cap for the interrupter mechanism, showing in elevation 70 the contact brush for making connection with the armature circuit. Fig. 11 is a rear view of the hub of the distributor arm. Fig. 12 is a detail view of a preferred form of the interrupter cam pins on the 75 armature shaft. Fig. 13 comprises face and edge view respectively of the washer used with the parts shown in Fig. 12.

In the embodiment of my invention herein selected for illustration, the magneto 80 proper comprises the base 1 on which are mounted the usual field magnets 2 (Fig. 4), between the poles of which is mounted the armature 3 carried by the shaft 4. The magnets and armature are preferably 85 enclosed within a casing comprising end plates 5-6 and the sheathing 7, by which the internal mechanism of the magneto is effectively protected from dirt and moisture. The magneto armature herein shown is of 90 the usual low tension type operating with a transformer coil 8 mounted in the bow of the field magnets, the general construction and arrangement of which are illustrated in my co-pending application, Serial No. 95 539,059 filed on the 20th day of January, 1910, to which reference is made for a full and detailed description of the parts co-operating with the invention herein described.

The armature shaft 4 as shown in Fig. 4 passes through the end plate 5 and is journaled within a plate 9 fixed to the lower portion of the end plate 5 and said plate 9 has formed thereon a cup bearing 10 for the 105 reception of the interrupter carrier. The interrupter comprises the annular carrier 11, Figs. 4, 6 and 7, preferably having a

- drawn-in flange 12 Fig. 6 at its inner end, through which the armature shaft 4 projects. (Figs. 3 and 4.) The fixed contact member 13 and the movable contact member 14 of the interrupter are mounted on a base plate 15, arranged to be secured to the drawn-in flange 12 by means of screws 16, (Fig. 3). The movable contact member 14 is pivoted at 17 to the base plate 15 and is in electrical connection therewith and said member preferably carries an anti-friction roller 18 to coöperate with cam pins 19 mounted on the armature shaft 4. In the preferred form, these cam pins 19 consist of pins frictionally mounted longitudinally in bores in the armature shaft 4, and lying partially within the circumference of the outer end of said shaft, and on opposite sides thereof. As shown in Fig. 12 the pins 19 preferably project beyond the end of the armature shaft 4 and are provided with grooves 19^a for engagement by pliers to facilitate removal of the pin. With this construction a filler washer 19^b is provided having notches 19^c fitting over the pins, to fill the space between the end of the shaft and the insulation for the contact pin 32 and to support said insulation. The roller 18 of the movable contact member 14, as indicated in Fig. 4, rides upon a reduced portion of the armature shaft and over the pins 19 to effect the interruption of the circuit. With the arrangement of the cam pins described, the latter may readily be adjusted to take up wear, by merely turning them up slightly to present a new surface to the anti-friction roller 18. The ends of the pin may be notched to facilitate this operation by a screw driver.
- The fixed contact member 13 of the interrupter is mounted upon, but insulated from, the base plate 15 and carries an adjustable contact point 13^a for the convenient adjustment of which the wall of the annular carrier 11 is provided with openings 11^a, 11^b, Figs. 6 and 7.
- The adjusting lever 22 for the interrupter is preferably fixed to the annular carrier 11, whereby the interrupter member may be shifted within the bearing 10 to vary the time of the breaking of the circuit with respect to the movement of the distributor arm.
- By the construction above described, it will be seen that the interrupter mechanism may be bodily removed from the bearing 10 after disconnecting the lever 22 from its operating connections.
- In order to determine the limit of adjustment of the interrupter with respect to the cam pins 19 on the armature shaft, the rear of the interrupter carrier is provided with a stop pin 23, (Figs. 6 and 7), adapted to engage either one of similar slots 24—24^a formed in the bottom of the bearing 10, ac-

cording to whether the interrupter is in right or left position.

In order to provide for both right and left drive of the magneto, the drawn-in flange 12 is provided with two sets of screw holes 25—25 and 25^a—25^a, either set of which sets may receive the screws 16 securing the plate 15 carrying the interrupter members. The interrupter carrier containing the contact members 13—14 may be removed bodily from the bearing 10 and the angular position of the contact members may then be shifted relatively to the shaft 4, by removing the screws 16 from the screw holes 25—25 and shifting the plate 15 carrying the contact members, 90° and again securing said plate in place by introducing screws 16 into the second set of screw holes 25^a—25^a. (Fig. 6.) The interrupter carrier may then be replaced in the bearing 10 in reversed position or with lever 22 extending to the side opposite its first position and will be then adapted to a reverse drive. Simultaneously with this shifting of the interrupter, the distributor is also shifted as later described.

The interrupter carrier 11 is provided with a removable cap 26 which may be held in place in any desired manner, but as here shown is provided with an improved sliding spring latch arm 27 having a key-hole slot 27^a fitting over a headed pin 28 mounted in the support 29 carrying the distributor mechanism hereinafter to be described. The upper end of latch arm 27 engages a stud 30 mounted on the cap or cover 31 enclosing the distributor. The lower end of the latch arm is provided with slot 27^c sliding on an insulating bushing on terminal stud 34, the face of said latch being in electrical engagement with the cap 26 to ground the stud 30 as set forth in my copending application 539,059 aforesaid. To remove the cap 26 from the interrupter it is only necessary to slide the latch arm 27 upwardly by means of its handle 27^b, until the larger portion of the key-hole slot 27^a comes opposite the stud head 28, whereupon the latch arm will spring free of the stud 28, and release both the caps 26 and 31 of the interrupter.

The electrical connections for the interrupter mechanism are effected as follows: Extending through the armature shaft 4 and insulated therefrom is a headed pin, indicated at 32, (Figs. 3 and 4), which is connected with the armature winding by means of a wire 33, Fig. 4. The cap 26 is provided with a terminal stud 34 insulated from said cap, as shown in Fig. 10, and carrying a brush contact 36 adapted to make electrical connection with the head of pin 32 at the end of the armature shaft when the cap is secured in position. Surrounding the stud 34 and in electrical connection

therewith, but insulated from the cap 26 is a disk 37, and mounted upon the fixed member 13 of the interrupter is a contact brush 38 adapted to engage the disk 37 when the 5 cap is in position. Thus the armature circuit will be carried through the pin 32, brush 36, disk 37 and brush 38 to the fixed contact member 13 of the interrupter and when the interrupter points are in contact, 10 it will be immediately grounded in the usual manner. The stud 34 has also a binding post or terminal head 39 from which a suitable connection may be made with the transformer coil in the manner indicated in my 15 co-pending application hereinbefore referred to. When the armature circuit is broken at the interrupter points, the current instead of being immediately grounded through the movable interrupter contact member 14 will 20 necessarily pass to the transformer coil through the terminal head 39 and to the connection leading therefrom.

Having thus described the construction and arrangement of the interrupter mechanism, it now remains to describe the construction by which the distributor arm may be adjusted or shifted to correspond to the 25 adjustments of the interrupter mechanism for right and left drive.

30 A distributor is located in the usual manner just above the interrupter and it comprises the several distributor segments 40, Fig. 3, which are suitably connected as at 41 to terminal heads 42, to which the connections with the spark plugs may be attached. The distributor arm 43 extends radially from a hub 44, which is removably and adjustably mounted upon a gear wheel 45, Fig. 4, driven by a gear wheel 46 on the 40 armature shaft 4, said gears being proportioned in the usual manner. The electrical connection of the distributor arm with the secondary winding of the transformer is not here shown, as this forms no part of the 45 present invention. In order to shift the distributor arm relatively to the distributor segments 40 to correspond to the adjustments of the interrupter for right or left drive, the gear wheel 45 is preferably provided with two threaded holes, Fig. 3, in either of which may be mounted a pin 49.

44^a is a hole or recess in the rear of the hub 44 of suitable size to receive pin 49. When the distributor is adjusted for a right- 50 hand drive, the pin 49 will be mounted as shown in Fig. 3 to properly position the distributor arm with respect to the cam pins 19-19. When the interrupter is adjusted for left-hand drive, the pin 49 will be 55 shifted to the other opening in the end of gear 45.

Having described the construction and arrangement of the interrupter and distributor in detail separately, I will now explain briefly the method of manipulation 60

by which these parts may be quickly adjusted relatively for right and left drive of the magneto shaft, whereby the device is adapted for universal application in any required position relative to the driving connections. 70

The gear 46 is so mounted on the shaft 4 with respect to the cam pins 19; the threaded holes for the reception of the pin 49 (designated for convenience L and R, respectively) are so arranged on the gear 45, and the gears are so relatively arranged initially as to bring the parts into the position shown in Fig. 3 for right hand drive. It is to be understood that in this position the 75 plate 15 carrying the fixed and movable interrupter contacts 13 and 14 respectively, is secured to the flange 12 of interrupter carrier 11 through the holes 25-25, designated for convenience R-R (i. e. for right hand drive). For earliest sparking, the lever 22 will extend to the right at an angle of about 80 45° above the horizontal, as indicated in dotted lines Fig. 3, as determined by the pin 23 Fig. 6 on the back of the carrier 11 85 and the slot 24 Fig. 5 in the bottom of the cup bearing 10. Now as the magneto shaft 4 turns to the right or clockwise, as viewed 90 in Fig. 3, the distributor arm and contacts and the interrupter contacts and cam pins 95 will be properly positioned for the required timing. To shift these parts for left hand drive of the magneto shaft, it is only necessary to slip the carrier 11 out of the bearing 10, shift the plate 15 and secure it 100 through the holes 25^a-25^a (L-L) Fig. 6 and shift the pin 49 of the distributor arm from hole R to hole L and finally replace the carrier 11 in the bearing 10 with arm 22 extending to the left (see dotted position Fig. 105 3) when the arm will again be in upper position for early sparking and the mechanism be ready for left hand drive as viewed in Fig. 3.

From the above described construction it 110 will be seen that the interrupter may be readily inspected while in operative position by simply removing the cap; and furthermore, the interrupter as a whole may be readily removed bodily from its support for 115 inspection and repair and also for the relative adjustment of the contact points. Moreover, this permits the shifting of the plate 15 carrying the interrupter members in the manner hereinbefore described, for 120 right or left drive.

What I claim is:

1. An interrupter for ignition mechanism, comprising in combination a fixed contact member, a movable contact member, means 125 for actuating said movable member, a shiftable carrier for said members having an open front, means whereby said contact members may be shifted on said carrier to adapt said interrupter for right and left 130

drive, and a cap covering the open front of said carrier removable to permit inspection of the entire interrupter mechanism when in operative position.

5. 2. An interrupter for ignition mechanism, comprising a fixed contact member, a movable contact member, means for operating said movable member, a ring carrier for said members having an open central shaft 10 passage, said members being located on the exposed side of said carrier, a bearing for said carrier, said carrier, together with said contact members, being adapted to be removed bodily from said bearing.

15. 3. An interrupter for ignition mechanism, comprising in combination a fixed contact member, a movable contact member, means for operating said movable member, a carrier for said members, a bearing for said 20 carrier constructed and arranged to permit the removal of said carrier and members bodily therefrom, and apertures in the side wall of said carrier normally covered by said bearing and rendered accessible by such 25 removal to permit adjustment of the contact points of said members relatively to each other without removing the members from said carrier.

4. In combination, a magneto including 30 a frame having a bearing, an armature journaled in said frame, an interrupter carrier mounted in said bearing and surrounding the shaft of said armature and carrying two contact members, one of which is movable, 35 means on said armature for operating said movable member, said carrier being constructed and arranged to be bodily removed from said bearing together with said contact members and replaced in said bearing 40 in reverse position, and means whereby said contact members may be simultaneously adjusted on said carrier to adapt said interrupter mechanism for right and left drive, means for shifting said carrier and contact 45 members in either position, with respect to said shaft, for timing purposes, and means for limiting such shifting movement in either position.

5. In combination, a magneto including a 50 frame having a bearing and an armature, a carrier having an open front mounted in said bearing and surrounding the shaft of said armature, a support shiftable in said carrier, a fixed contact member and a movable contact member carried on the outer side of said support, means on said shaft for operating said movable member, and means to establish the position of said shiftable support on said carrier for either a 55 right or left drive, said carrier being constructed and arranged to permit the inspection of the interrupter mechanism when in operative position.

6. In combination, a magneto including 60 an armature and a distributor, a carrier sur-

rounding the shaft of said armature and carrying a fixed contact and a movable contact, means on said shaft to operate said movable contact, said contacts being constructed and arranged to be adjusted within, and relatively to, said carrier to adapt the interrupter to right and left drive, a gear on the armature shaft, a second gear driven thereby, a removable distributor arm carried by said second gear, means for adjustably mounting said distributor arm on its gear and means for coördinating said adjustments with the adjustment of the interrupter mechanism for right and left drive. 70

7. In combination, a magneto including an armature, a shaft therefor, a reversible contact carrier surrounding one end of said shaft, a bearing for said carrier, an adjustable support within said carrier, contact members mounted on the outer side of the latter, one of said contacts being movable, means on said shaft for operating said movable contact member, and means to establish the position of said shiftable support 85 on said carrier for either a right or left hand drive. 90

8. In combination, a magneto including an armature, a shaft, a shiftable carrier surrounding said shaft, two contact members 95 carried by said carrier, one of the same being movable, means on said shaft for operating the latter, an armature terminal mounted in said shaft, a removable cap for said carrier having a contact brush mounted thereon for removal therewith adapted to engage said terminal, a contact point on said fixed contact member, and means for causing said contact point to effect electrical connection with said contact brush when 100 the cap is in position on said carrier. 105

9. In combination, a magneto including an armature, a shaft therefor, a shiftable carrier surrounding said shaft, a fixed contact member and a movable contact member 110 mounted in said carrier, means on said shaft to operate said movable member, an armature terminal mounted in said shaft, a cap removably mounted on said carrier, and means for automatically effecting electrical 115 connection between said terminal and said fixed contact member when said cap is positioned on said carrier. 120

10. In combination, a magneto including an armature, a shaft therefor, a carrier surrounding said shaft, two contact members, one being movable and mounted in said carrier, a cam member on said shaft to operate said movable member, the cam being adjustably mounted on said shaft and relatively to said movable contact member to present fresh bearing surfaces to said member to compensate for wear. 125

11. An interrupter for ignition mechanism, comprising a magneto including an 130

5 armature and armature shaft, a carrier surrounding the end of the shaft of said armature, a fixed contact and a movable contact mounted in said carrier, a pin located longitudinally in and partially embedded within the circumference of said shaft, the projecting portion of said pin coöperating with said movable contact to operate the latter, said pin being arranged to be turned to 10 present to said movable contact different operating surfaces.

12. An interrupter for ignition mechanism, comprising in combination a magneto including an armature, an armature shaft, 15 a gear on said shaft, a second gear driven by the first, and a rotatable distributor including a laterally extending distributor arm carried by said second gear, a carrier surrounding the shaft of said armature, a 20 fixed contact and a movable contact mounted in said carrier, and including a shiftable contact support, means on said shaft for operating said movable contact, means to establish the position of said shiftable support on said carrier for either a right or 25 left rotation of said shaft, and means for correspondingly shifting said distributor arm to coöperate with the adjustment of said interrupter contacts.

30 13. An interrupter for ignition mechanism comprising two contact members, one of which is movable, means for operating the movable member periodically, an open front detachable ring support upon which 35 said members are mounted, and a cap covering the open front of said support removable to permit inspection of said members when in operative position.

40 14. An interrupter for ignition mechanisms comprising two members, one of which is movable, means for operating the movable member periodically, a detachable ring support open at its outer end and carrying said members at its inner end, and a 45 removable cover for the outer end of said ring support.

15. An interrupter for ignition mechanisms comprising two members, one of which is movable, means for operating the 50 movable member periodically, an annular plate support upon the outer side of which said members are mounted, and a shiftable carrier for said plate, said plate being adjustable in said carrier to change the position of said movable member relatively to its operating means.

60 16. An interrupter for ignition mechanisms, comprising two members, one of which is movable, means for operating the movable member periodically, a detachable ring support for both of said members, a bearing support for said ring, said ring being adjustable therein to change the position of the same relatively to said operating 65 means for the movable contact member, one

of said contact members being adjustable, and an opening in said ring to afford access thereto, said opening being closed by said bearing when the parts are assembled.

17. In a magneto, an interrupter comprising two contacts, one of which is movable, means for periodically operating said movable contact, means for driving the latter in one direction or the other, a support for said contacts, means for shifting said contacts relatively to the means for operating the movable contact, a distributor including a distributor arm, means for rotating the distributor arm and operating the movable contact of the interrupter in synchronism, and means for bodily shifting the parts of the interrupter and the distributor arm a predetermined and corresponding amount to adapt the magneto to right or left hand drive, said means being independent of the first mentioned shifting means for the interrupter.

18. An interrupter for ignition mechanism comprising a magneto including an armature, an armature shaft, a carrier surrounding the end of the shaft of said armature, a fixed contact and a movable contact mounted on said carrier, a pin located longitudinally in and partially embedded within the circumference of said shaft, the projecting portion of said pin coöperating with said movable contact to operate the latter, said pin having tool engageable means to facilitate withdrawal thereof from said shaft.

19. An interrupter for ignition mechanism, comprising a magneto including an armature, an armature shaft, a carrier surrounding the end of the shaft of said armature, a fixed contact and a movable contact mounted on said carrier, a pin located longitudinally in and partially embedded within the circumference of said shaft, the projecting portion of said pin coöperating with said movable contact to operate the latter, said pin projecting beyond the end of said shaft and having tool engageable means on said projecting portions to facilitate removal of the pin from the shaft.

20. An interrupter for ignition mechanism, comprising a magneto including an armature, an armature shaft, a carrier surrounding the end of the shaft of said armature, a fixed contact and a movable contact mounted on said carrier, a pin located longitudinally in and partially embedded within the circumference of said shaft, the projecting portion of said pin coöperating with said movable contact to operate the latter, said pin projecting beyond the end of said shaft and having tool engageable means on said projecting portion to facilitate removal of the pin from the shaft, an insulated headed contact terminal mounted longitudinally in said shaft, and a filler washer on the end of

the shaft flush with the outer end of said pin to fill the space between said shaft end and the head of said terminal.

21. An interrupter for ignition mechanism comprising a magneto including an armature, an armature shaft, a carrier surrounding the end of the shaft of said armature, a fixed contact and a movable contact mounted on said carrier, a pin located longitudinally in and partially embedded with in the circumference of said shaft, the pro-

jecting portion of said pin coöperating with said movable contact to operate the latter, said pin having tool engageable means to facilitate withdrawal thereof from said shaft, said pin being arranged to be turned to present different operating surfaces to said movable contact. 15
